SUPPORTING, COOLING, AND LUBRICATING
MEANS FOR HIGH-SPEED SHAFTS OR
SPINDLES

Mario Consigliere, Genoa-Nervi, Italy

Application December 17, 1938, Serial No. 246,475
In Italy December 21, 1937

6 Claims. (Cl. 51—166)

This invention relates to an apparatus for grinding small bores.

It is known that the grinding of small bores still meets with difficulties the first of all being the high angular speeds required for such work. In fact, for a good production and a careful finishing it is necessary that the peripheral speed of the grinding tool be kept between 20 and 30 metres per sec. For instance, for grinding a bore having a diameter of 6 mm. by using a grinding wheel having a diameter of 5 mm. by a peripheral speed of 25 m./sec., the angular speed of the tool must reach 100,000 revs. per min. Further, if the bore has a considerable depth, and at present such depth equals in many instances ten times the diameter of the bore, it is necessary to employ very long and fine spindles. Always considering a bore of 6 mm. the spindle should have for such depths a length of about 60 mm. and a diameter of not over 4 mm. in order to bear at its end a grinding wheel having a diameter of 5 mm. When considering that the total amount of overhanging from the bearing could not be less than 70 mm. the theoretical critic speed of such a spindle would be of 34,000 revs. only, i. e. almost one-third of the angular speed required for a good operation of the grinding wheel.

In order to reach speeds above 100,000 revs. and to eliminate the other causes which hindered up to now the performance of such works, a type of spindle has been designed which, widely differing from those now in use, fully answers the different requirements that I am going to shortly point out hereinafter.

The rotating part must be very light, guided by multiple bearings and have a modulus of resistance that is higher than that overhanging rotating solid spindles now in use. Further it is necessary to readily disperse the intense heat evolved due to friction to cool both the grinding wheel and the workpiece, to blow off the dust formed by grinding and to conveniently lubricate the bearings.

Such problems and still some other ones connected with the construction of devices for the grinding of small bores having a grinding wheel-carrying spindle driven at very high speeds, have been brilliantly resolved in the manner that shall clearly appear from a practical embodiment which is shown by way of a non-limiting example in the annexed drawing, in which:

Fig. 1 is an axial section of the forepart of a spindle for grinding small bores, based upon the principle of the present invention;

Fig. 2 is a reduced section of the rear part of same spindle;

Fig. 3 is a front view on enlarged scale of the same spindle.

The spindle shown in the drawing is designed for the grinding of small bores. It is known that as a grinding wheel must have a peripheral speed of 20 to 30 meters per sec. and when grinding bores having a diameter of less than 1 cm., by employing a grinding wheel having a diameter of say 5 mm., the spindle must turn at 100,000 revs. p. min.

At such an exceedingly high speed, and even at a substantially lower number of revolutions, it is practically impossible to provide for an efficient cooling by the ordinary means and also the lubrication appears practically impossible by the usual means, as an oil film of a certain thickness practically acts as insulating means and being strongly laminated contributes towards an increase of friction.

According to the present invention the above inconveniences are overcome as follows:

At least one of the rotation bearings of spindle V and in this instance the outer end bearing X of the shaft, has a perfectly adjustable clearance and is provided with longitudinal grooves, through which a current of cooling fluid having leached the parts rotating at high speed is discharged.

Said fluid, generally consisting of compressed air, is conveniently oiled or otherwise greased, before it reaches the rotating parts, by causing it to pass through a felt, pad F or other porous diaphragm imbibed with oil or like lubricating means. In the present instance the imbibing of felt F with oil is obtained by causing a part of said felt to dip into an oil chamber 13.

By way of example I am going to describe in the following an improved tool for the grinding of small bores, constituting a considerable improvement over all like tool and embodying the above principles, though it is understood that the same system can apply to any tool having a spindle or shaft, driven at high speed either by a turbine wheel, as in the present instance, or by other means, such as electrical motors or the like.

The device comprises a cylindrical casing 4 in the cylindrical fore part of which a cylindrical block I is slidably mounted. The block I has at its periphery a number of axial grooves which, together with the adjacent walls of casing H, define conduits 5 for the passage of fluid.

In the fore part of block I a turbine wheel O is

mounted, having a projecting hub 6 mounted on convenient bearings N—N' acting as rotation and thrust bearings. Hub 6 is axially bored and extends through the bottom of a cup-shaped part

- 5 M abutting on one side against the outer race of bearing N and on the other side against a screw threaded axially bored disk L, through which therefore the axial position of bearings N—N' may be registered. Block I is fitted at its outer
- 10 end with an annular disk P carrying nozzle 7 in communication with air duct 5 and arranged in such a manner as to discharge the air through the turbine wheel O and to enact on the latter an inward thrust, in the direction of bearings
- 15 N—N'. The outlet of air from the turbine wheel to the exterior is effected through chamber 8 of block I and port 9 of casing H.

To the outwardly projecting threaded hub part 6' of turbine wheel O the spindle V is fitted by means of an inwardly flanged nut T, bearing against the abutment washer 10 of spindle V. Spindle V is rotatably fitted in bearings U and X. Bearing U is fitted within a cavity of flanged disk member 11 having as outer central extension the supporting sleeve W. This sleeve is bored axially, but in the present case, where a boring spindle is concerned, an eccentric bore, as shown in Figs. 1 and 3, should be preferred. The outer end of the spindle bore is flared to receive the plug-like outer bearing X having, like the corresponding outer part of the spindle a preferably conical bore and is provided with longitudinal or also helical (Gleason) grooves to enable the refrigerating fluid to pass from the interior of sleeve 35 W to the exterior.

The spindle bearing disk 11 is kept in place on casing H by a collar R and a screw-threaded ring S.

The axial position of block I can be registered by means of screw-shaft D under the action of a spring C, and which can be shifted axially along the outer annular chamber of casing H by means of a screw-sleeve 12, abutting against a plug-like closure member E fitted to the end 45 of casing H.

By the axial shifting of the shaft D and of the block I, the position of spindle V within its supporting sleeves W can be registered. In consideration of the fact that the outer end of the 50 spindle is conical, it is apparent that by axial shifting of said sleeve the clearance space between the outer end of spindle V and its bearing X can be exactly registered.

The annular chamber 17 is filled at its lower 55 part with oil. This chamber is formed by inserting co-axially with casing H a pair of flanged sleeves 14—14', between which a felt pad F is inserted, so as to dip in the oil of chamber 17. Sleeve 14 is fitted on an air inlet nipple G on 60 which a pressure spring A is arranged.

A portion of the pressure air is led through port 16 in the upper part of chamber 17, and through ducts 5 and 18 to turbine nozzles 7. Another portion of the air is deflected through 65 pad F dipping into the oil 13 filled into the lower part of annular chamber 17 through screw plug B. This air thus oiled after having traversed this pad, passes through the sleeve portion 14' through the small bore 19 of the screw-disk 70 L, then it expands in the chamber 20, where it is cooled and deposits any eventual excess of oil. A part of said oiled air is discharged through the axial bore of hub 6 of the turbine wheel and the axial bore 21 of the first part of spindle V 75 and cross bores 22 of said spindle. From said

cross bores it is discharged between the spindle V and its supporting sleeve W leaching these parts throughout their length and is led out through the longitudinal grooves of bearing X and cools the grinding wheel Y and blows out the 5 dust of grinding.

Another portion of the air from chamber 20 is led through a filter through the bearings N—N' and to the exterior through part 9.

Due to the fact that this air does not carry 10 an excess of oil, the grinding wheel and other rapidly rotating parts do not become exceedingly lubricated and the work is performed more smoothly.

Furthermore, due to the excentrical bore of 15 sleeve W, the grinding wheel Y can work almost to its complete wearing out, which is very important in view of the exceedingly small diameter of such wheels. The change of this wheel Y is very easy, as it is sufficient to loosen a screw 20 Z. It is also possible to change with outmost facility spindle V and sleeve W, as well as to angularly adjust sleeve W in connection with the nature of work to be performed, all due to the above described mounting. 25

From the preceding it is apparent that the new spindle represents a substantial improvement over the tools of this kind hitherto known. In fact, due to the improved construction and arrangement of the parts and especially of the 30 turbine wheel and to the cooling and lubricating means, angular speeds as high as 100,000 R. P. M. and more are possible, while keeping the working parts substantially cool.

It is also apparent that the present invention 35 is not confined to the special construction here illustrated by way of an example.

I claim:

1. An abrading tool comprising in combination: one casing, a block slidably arranged upon 40 said casing, a turbine wheel having an axially bored hub fitted within said block and rotatably mounted on rotation and thrust bearings; a nozzle carrying disk fitted at the end of said block, with nozzle blowing against the turbine wheel, a 45 discharge chamber provided within said sliding block and in communication with an outlet port of said casing, a spindle having abutment means mounted within the end of the bore of the turbine hub, a screw-threaded flanged nut coacting 50 with the turbine wheel hub and abutment means of the spindle, for keeping the spindle in position; a flanged disk fitted at the end of said casing, an overhanging sleeve member integral with said disk and projecting outwardly, through 55 which the outer part of the spindle is passed, a pair of bearings for the spindle at both ends of said sleeve, grooves cut through the inner surface of the outer bearing, an air duct axially traversing the rear part of said spindle and with a 60 transverse opening near the inlet end of said overhanging sleeve; means for feeding pressure fluid to the turbine wheel and means for feeding oiled air through the turbine bearings and along the bore of turbine hub, from the rear part of 65 spindle, as well as along the sleeved outer spindle surfaces and, through the grooves of the outer bearing, against the abrading or grinding wheel.

2. An abrading tool according to claim 1, in which the bore of the overhanging sleeve is 70 eccentric and the outer end of the spindle and of its bearing are conical.

3. An abrading tool according to claim 1, in which the outer end of the spindle and its bearing are conical and comprising further means 75

- for enacting an axial sliding of the spindle-carrying block; means for shunting one part of the air admitted to the turbine wheel through an oiled pad; an expansion chamber for the oiled air, whereby, by an axial shifting of said spindle bearing block, the axial position of the spindle may be varied with regard to the outer conical bearing, thus registering the clearance space existing between the end of the spindle and the corresponding bearing and accordingly varying the amount of air blown out through said conical bearing.
5. An abrading tool comprising in combination an action turbine wheel mounted on rotation and thrust bearings; means for feeding air to said turbine wheel so as to rapidly rotate same as well as to impress on the same an axial thrust in the direction of the thrust bearings; a spindle fitted on said turbine wheel, bearings at 10 the ends of said spindle, means for feeding oiled air through those parts of the turbine wheel bearings extending along the spindle and be-
- tween the spindle and its end bearing, an eccentrically bored, overhanging sleeve enclosing and stiffening the overhanging part of the spindle; a grinding wheel fitted at the free end of said spindle and a screw keeping this grinding wheel 5 in place.
5. An abrading tool, according to claim 4, wherein an outer casing is provided and divided into two co-axial longitudinal sections, one of which containing the ducts for the admission of 10 air, and the other the means for axially registering the turbine wheel and spindle carrying block as well as an oil reservoir and a pad inserted in the said oil reservoir and extending through the 15 passages for the cooling air to be oiled for lubricating purposes.
6. An abrading tool according to claim 1 which further comprises means for leading air under pressure through a pad constantly imbibed with oil.
